FOOT-OPERATED GUITAR PLAYER

Walter C. Sylvester, Greene, Maine

Application August 7, 1939, Serial No. 288,724

9 Claims. (Cl. 84—320)

This invention relates generally to mechanically operated players for stringed musical instruments such as guitar, ukulele, banjo, mandolin and the like, more especially to guitar and ukulele.

Among the more important objects of this invention is to provide a device to enable a person to play a guitar or ukulele for accompaniment in conjunction with another instrument played by hand. It is also an object of this invention to provide a device of this character which requires a minimum of physical effort and mental attention.

Another object of this invention is to provide a machine of this character which is inexpensive to manufacture, neat in appearance, efficient in operation, durable for service, excellent in tone quality, light in weight and convenient to carry.

Among the important advantages of a machine of this character is that the instrument may be fastened in playing position or removed from machine very quickly and easily and is completely adjustable to any ordinary sized instrument; also the instrument may be tuned without removing from the machine.

Comprised in this machine are means for holding the instrument securely in position relative to the machine, means for stopping or pressing strings at the proper position to produce a desired tone when instrument is in correct tuning and when strings are plucked, means for producing a series of "groups of tones" or chords without making any change in the composition of the machine, such means including pedal operated by the left foot of the operator, means for plucking any one of the three bass strings, the three treble strings in unison or all six strings at one stroke, either on the down stroke of the pick or on both the down and up strokes such means being operated and controlled by the right foot of the operator, strings being selected by a slight movement of the right knee.

Notable in the construction of a device of this character is the pick which is made of leather or similar material in a folded position and having the quality of being smooth but comparatively soft and flexible so that when it plucks the string or strings no sound is produced by the pick itself, but due to the flexibility and smooth surface of the pick, the string is pressed in a horizontal direction and toward the body of the instrument as the pick passes by it, therefore causing the string to vibrate "toward and from" the sound

hole instead of across, thereby producing a deeper, more pleasing tone.

Another notable feature is that the machine will fold up into one compact unit and can be enclosed in a box-like frame for easy conveyance and is comparatively light in weight and small in size.

The invention will be fully understood by the following specifications when read in conjunction with the accompanying drawings.

In the drawings:

Fig. 1 is a top plain view of the fret control mechanism.

Fig. 2 is a back elevational view of the fret control mechanism partly in section.

Fig. 3 is a sectional elevational view of chord insert and insert holder and a sectional end view of push rods.

Fig. 4 is a side view of instrument support located near the base of the machine.

Fig. 5 is instrument holder located at top of machine.

Fig. 6 is knee control attachment located at top.

Fig. 7 is a sectional elevational view of pick control mechanism.

Fig. 8 is a sectional side view of runway in which pick arm travels.

Fig. 9 is back or inside plain view of pick arm runway with pick arm in position.

Fig. 10 is back or operator's plain view of complete machine.

In the invention herein illustrated by accompanying drawings, the so-called "nut" of the instrument or that portion of the neck which holds the strings in the proper position, is held securely against the bumper 18 by clamp 20 which is designed to receive a portion of the neck and is hinged at the bottom end, the top end being held in place by a winged nut 21 and threaded pin 21A. Member 30 generally designated in Fig. 5 is inserted in socket 17 to hold the top side of the body of the instrument against the stop 76.

The bottom side of the instrument is supported by members generally designated in Fig. 4 consisting of a tube or pipe 23 with two nuts 24 at one end which are tightened onto frame to hold securely in position. The inside of tube 23 is designed to receive a square shaft 25 which will slide in and out but will not turn nor twist. Means designed to receive the body of the instrument, illustrated at 27 is attached to the end of shaft 25 by nuts 28. Adjustable nut 26 holds shaft 25 from sliding too far into tube 23.

thereby holding the instrument too close to the pick. Shaft 25 is held securely in position in pipe 23 by thumbscrew 29 which may be tightened after shaft 25 is inserted.

The fret control mechanism generally illustrated in Fig. 1 comprises L shaped fingers 11 which are of spring wire or similar material having leather tips 12 and a loop in the other end as provision to associate with slidably located pushrods 13 which are held back by springs 14 and clips 15 fastened securely to the ends of pushrods 13 to prevent springs from coming off. Pushrods 13 are passed through holes in frame 16 in formality as in Fig. 3 so that the prongs 22A on chord insert 22 will pass through the group of pushrods 13, more fully illustrated in Fig. 3. Fingers 11 are pivotally attached at 17 so that when pushrods 13 are pushed contrary to springs 14, the leather tips 12 are pressed down onto the strings, forcing them onto frets adjacent the finger, being six rows of fingers, one row for each string and as many in a row as the number of frets to be controlled.

Pushrods 13 have flat places 13A cut in them on top and bottom and about one inch apart. These flat places are about one-half inch long and leave shoulders at each end for chord insert portion 22B to abut against when inserted in holder 19 and pressure is applied. When chord insert 22 is in holder 19 projections 22B are in contact with certain and particular pushrod shoulders at the end of flat surfaces 13A and when pressure is applied projection 22B on chord insert abut against shoulder forcing slidable member 13 ahead or to the left, thus forcing finger tip 12 onto string; but where there are no projections 22B the slot in insert 22 is wide enough to pass by the shoulder and leave pushrod in natural position, thus the chord insert is made with projection 22B to correspond with the desired notes to be played and all strings may be stopped at the proper place so that they will be in harmony with a particular chord. For different chords different inserts are used. The flat surfaces or cut-outs are made one-half inch long to allow push rod to be moved to the left by different chords using the same note or pushrod. There are eight different chord insert holders which may be filled with any chord inserts that are desired. Insert holders are of L shape pivotally attached to frame near the base of the machine, shown in Fig. 10 with provisions to contact with roller 85 on the end of pedal 82 which is for the left foot, such provisions being at the left end of L shaped insert holders. Pins 86 are located between each contact surface in such a position as to prevent roller 85 from pressing two chord insert holders at the same time, but the proper distance apart to allow roller to go between said pins, therefore pressing only one chord.

Pedal 82 is hinged to frame at the heel end in such a manner as to allow the toe end to move to the right or to the left and also up and down, 65 further explained later in this specification.

Fig. 7, Sheet 2 illustrates the picking mechanism. Pick 31 is of soft and smooth finished leather or similar material folded and mounted on pick arm 33 by bolt 32 in such a position as 70 to allow flat surface of pick 31 to contact with the strings, the folding of the leather for the pick being to form a blunt surface for the string to slide off from when picked, this having a tendency to press string toward the body of the 75

instrument, causing string to vibrate "in and out" of sound hole instead of across, therefore producing a deeper tone than would be produced by an ordinary pick which pulls the string down and snaps off suddenly.

Pick arm 33 is mounted on a sliding member 34 by a hinge joint at the bottom and means comprising a rocker 35 pivotally attached at the center by rivet 36 to the top end of sliding member 34. The top end of pick arm 33 is attached to the top part of rocker 35 by sliding pin 40 which allows the top of pick arm and rocker to come closer together but prevents the same from becoming too far apart. Compression spring 46 holds pick arm 33 and rocker 35 apart unless contrary pressure is applied.

Control arm 37 is attached to the outer side or edge of rocker 35 by a rivet 38 opposite or at the same level as rivet 36. Friction 43 is of felt or 20 similar material and has a spring tension 44 adjustable by thumb screw 45, located at the back. This friction resists the movement of the slide 34. Therefore, when the control arm 37 is pushed upward, instantly the top of the rocker 25 35 is pulled back and thus the pick arm and pick which are connected by means including a link 40. Pin 41 strikes rocker 35 and prevents the latter from going too far in that direction. When pin 41 strikes rocker 35 slide 34 starts to 30 slide upward and so continues to the end of the upward stroke. When the direction of control arm 37 is reversed and starts downward, thus pushing top of rocker 35 ahead or toward the instrument, pick 31 contacts with the strings of 35 the instrument. Stop 42 prevents pick arm from going too far ahead.

Roller 47 is similar to a wheel with a rubber tire mounted at or near the center of the pick arm 33 which rolls on or follows a corduroy track, 40 thus holding the pick arm and pick away from the strings except when a hollow or dip is made in said track; spring 46 holds pick arm and roller 47 against corduroy track Fig. 8.

If it is desired to pluck the strings or string on 45 both the down and up strokes, the roller 49 which is attached to the extreme top of rocker 35 is in line with the top of track 48. Therefore, if track 48 which is attached at the bottom to the base of the machine, be moved ahead or toward the instrument thus pushing roller 49 and the top of rocker 35 in the same direction, rocker 35 is held in the same position on the up stroke as it is on the down stroke, therefore the strings are picked on both the up and down strokes.

55 There are two ways or means for holding this track 48 in the above named position. First, by tightening thumb screw 48A onto track 48. Track may be held in any desired position, being held back by spring 54 which holds lever 52 and rod 53 up. Rod 53 is connected to the upper end of L shaped lever 50 which is pivotally attached at the upper corner to the frame, the lower end being connected to track 48 by connecting rod 51. Therefore, by holding lever 52 down, track 48 is held against roller 49 and roller 49 rolls up and down with comparatively little resistance on track 48.

It is understood that lever 52 is held down by the toe of the right foot, therefore the heel must be raised and lowered to actuate the picking contrivance. (Note the construction of the pedal arrangement.) In other words, in simple or straight time the picking is done by raising and lowering the toe of the right foot but if it is desired to play eighth notes or two notes in the

place of one using the "up" stroke, the toe is held down and the heel raised and lowered for that particular note or notes; but if the whole piece is to be played fast or in "cut time" the thumb screw 48A may be tightened, thus holding pick onto strings at both the up and down strokes and the pick may be actuated by the toe as usual.

Fig. 8 and Fig. 9 show the construction of the corduroy runway or track in which roller 47 runs. The track or runway is constructed of flat pieces of metal or slats 56 forming the surface and these slats are slidably located on pins 57 and held against frame by springs 58. The holes in slats 56 are large enough to allow tipping as rollers 59 pass over them and press them flat against frame when rollers 59 are not in contact with them.

Rollers 59 are mounted on movable frame 60 and are held against slats 56 by other and smaller grooved rollers 61 which also are mounted on frame 60 and roll on tracks 62. Rollers 59 as they pass over slats 56 press them down and make a dip or hollow in the runway. This dip corresponds to one string, that is to say when roller 47 passes over this dip the pick is allowed to pick a certain string provided that the dip is in the proper place. This dip is movable from one string to another by moving frame 60 and therefore, rollers 59 controlling only the three base strings. The three treble strings are almost always played together in playing chords, therefore provisions are made as follows: When frame 60 and rollers 59 are pulled down as far as possible rollers 59 press the top end of plate 63 in or away from this frame and at the same time rollers 64 which are also attached to frame 60 press the lower end in. Plate 63 is constructed to receive rollers 64 at this time and at no other time are rollers 64 used.

The corduroy track assembly is hinged at the top to allow the same to be moved away from pick arm 33 and roller 47, thus six note chords may be played. The bottom of the assembly is held to frame by means comprising springs 65 and bolt 65A, one on each side of the track assembly. Spring 65 and bolt 65A hold the track assembly in normal position unless lever 66, shown in Fig. 10, is pulled down, thereby pulling the track assembly away from the frame of the machine and also the pick arm 33. Therefore roller 47 does not bear on track and the pick is allowed to come in contact with the strings during the entire stroke.

Frame 60, on which rollers 59, 61 and 64 are mounted, is controlled by means including an L shaped piece 67, which is pivotally attached to frame at the corner and to movable frame 60 at the upper right end and to connecting link 69 at the lower left end. Link 69 is also attached to control arm 68 which, in turn, is securely fastened to shaft shown in Fig. 7. Shaft 70 has a bearing at the bottom end on the base of the machine and one near the top 75, thus holding shaft securely but allowing it to turn. A ball and socket connects arm 68 and link 69 to allow them to move freely.

Member 11, Fig. 6, which is instantly detachable, is attached to the upper end of shaft 70 and extending toward the operator and is designed to receive the knee or a portion of the leg; thus when the knee is moved slightly from side to side, a turning or twisting motion is encountered on shaft 70, thereby moving arm 68 in the same manner. L shaped lever 67, being connected by link 69 at the lower end, is moved also, but the

upper right end which is connected to frame 60, moves up and down instead of from side to side, because of the L shaped construction, thereby moving frame 60 and the attached rollers up or down.

L shaped member 67 is equipped with a roller 72 which rolls on the track or arm 73. This arm is designed with notches for roller 72 to stop in as it passes up and down. Spring 74 is connected to the frame and also to arm 73 to hold arm 73 tight against roller 72; thus, due to the spring quality of member 71 the knee may be moved slightly without moving frame 60. In other words, the knee does not have to be in the exact position to enable the operator to strike a certain string, but if the knee is moved sufficiently to one side, roller 72 will roll over the point on arm 73 and fall into the next notch, thereby allowing the pick to strike the next string.

Number 76 is an adjustable stop to hold the instrument in the correct position in relation to the pick. The right foot of the operator is securely fixed to pedal 78 by straps or other device to insure that the action of the pedal 78 is completely controlled by the foot. Pedal 78 is pivotally attached to members 80 by rivets or bolts 79 and is so constructed that the lever 52 may be held down by the toe and the heel raised and still have the same effect on control arm 37, as if the heel were held down and the toe raised. Members 80 are pivotally attached adjacent the floor of the machine by rivets or bolts 81 and also to control arm 37; the comparative distance from points 79 to 81 is much shorter than from 79 to the control arm 37. This is to reduce the travelling distance of the foot.

The left foot is to be attached to pedal 82, which is hinged at 83 and is pivotally attached at 84 and is equipped with a roller 85 which has a surface of leather or some soft material. This roller is designed to roll along on shelf-like portions of chord arms located at the base of the machine in Fig. 10 between which are located pins 86 which prevent the roller 85 from pressing two "shelf-like portions" of chord arms at the same time. The roller and therefore the pedal 82 has to be raised over the pins 86 before a change of chords can be made.

Members 87 are designed to receive straps to attach the pedals to the feet.

The floor of the machine or that portion which supports the pedals is hinged to the base of the machine proper by bolts 90 and is held securely in place by braces 88 and 89. These braces will fold up, therefore allowing the floor of the machine and pedals also to be folded into a vertical position, therefore, requiring very little space when not in use. The machine may be enclosed in a neatly appearing box which may serve as a part of the frame.

It is apparent that modifications of the present invention can be made without departing from the scope thereof, such as the design of the pedals and other parts of the machine, materials used in construction, means for folding.

It is understood that this invention is capable of extended application and is not confined to the exact showing and description. Therefore, such modifications may be made as do not alter the spirit of the invention or exceed the appended claims.

I claim:

1. In a machine for playing a stringed musical instrument a mechanism for stopping the strings including a group of fingers pivotally attached to

a frame and arranged adjacent the strings of the instrument each occupying a position relative to a certain string at a certain fret of said instrument, a group of pushrods equal in number to said group of fingers and arranged in a position to actuate said group of fingers individually, a series of plate holders movably held adjacent said pushrods and designed to receive a plate fitted to the same, a group of levers pivotally attached to the base of frame and a pedal.

2. In a machine for playing stringed musical instruments a mechanism for stopping the strings including a group of fingers with tips insulated with rubber, leather or the like and being pivotally mounted on a frame in a uniform manner, each said finger tip being in a position relative to and opposite a certain string at a certain fret, an equal number of pushrods arranged in a position to actuate said group of fingers, each pushrod having a plurality of shoulders spaced an equal distance apart, a spring associated with each pushrod and finger, a series of plate holders movably held adjacent said group of pushrods and designed to receive a plate of certain dimensions an unlimited number of said plates, a series of levers pivotally attached to the base of the frame and associated with said plate holders and a pedal pivotally attached to the frame of the machine.

3. In a machine for playing stringed musical instruments mechanism for actuating fingers for stopping the strings including a group of pushrods arranged in a uniform manner to correspond to the arrangement of fingers, each pushrod having shoulders spaced an equal distance apart, a series of plate holders identically the same in shape and size, movably supported adjacent said group of pushrods, a plurality of plate inserts interchangeable one with another, a series of levers pivotally attached to the base of the frame and associated with said plate holder supports, a pin between each lever and a pedal having a roller at the end.

4. In a machine for playing stringed musical instruments means for picking the strings including a pick arm supporting a pick at the upper end and having a roller mounted thereon and being pivotally attached to a slidable member at the lower end, a rocker also attached to said slidable member and connected to said pick arm, a pedal pivotally mounted and associated with said rocker and pickarm by means including an arm and a connecting link.

5. In a machine for playing stringed musical instruments means for picking the strings including a pick mounted on a pickarm, said pickarm being pivotally attached to a slidable member supported in an upright position, a friction associated therewith, a rocker also pivotally attached to said slidable member and connected to said pickarm, a pedal pivotally mounted on a frame suitable for a machine of this type and associated with said pickarm and rocker by means including an arm and connecting link.

6. In a machine for playing stringed musical instrument, means for picking the desired string or strings including a pick mounted on and controlled by a pickarm, said pickarm being pivotally attached to a slidable member and having a roller thereon, said slidable member being supported in a vertical position and associated with a friction, a rocker pivotally attached to said slid-

able member and also connected to said pickarm by means including a link and a spring, a runway for previously mentioned roller on pickarm, having a changeable surface, means for changing the surface thereof including rollers mounted on a slidable frame and a lever adapted to the knee of a human being, means for actuating said pickarm and rocker including a pedal pivotally mounted on a frame suitable for a machine of this type, an arm and a connecting member.

7. In a machine for playing stringed musical instruments, means for selecting the string or strings to be picked including a runway for a roller mounted on a pickarm, said runway having a changeable surface, means for changing said surface including a slidable frame having rollers mounted thereon, a lever pivotally attached to the frame of the machine and being adapted to the knee of the human being and also being connected to said slidable frame by an arm and a connecting link.

8. In a machine for playing stringed instruments, means for selecting the string or strings to be picked including a frame, a runway for a roller on a pickarm, said runway being pivotally attached to the frame of the machine, means for controlling the position of said runway including springs and a lever, said runway consisting of a frame, slat like sections arranged horizontally and in parallel, each section being supported individually by pins and springs; means for changing the surface of said runway including a frame slidably and securely held in a vertical position close to said runway and having rollers mounted thereon, means for moving said frame and rollers to a desired position including a lever adapted to the knee of a human being and connected to said slidable frame by means including an arm and a connecting link, said lever being pivotally attached to the frame of the machine; a notched member associated with a roller, notches being spaced relative to the spacing of the strings of the instrument.

9. In a machine for playing stringed musical instruments, means for picking the desired string or strings including a pick mounted on a pickarm, said pickarm being pivotally attached to a slidable member, a rocker also attached pivotally to said slidable member and connected to said pickarm by means including a link and a spring, a friction associated with said slidable member, said pickarm and slidable member being supported in an upright position, a roller mounted on said rocker, a movable track adjacent said roller, means for controlling said track by hand including a thumb screw, and by foot including a lever, a connecting link and a spring; a pedal pivotally attached to the frame of the machine and associated with said pickarm and rocker by means including an arm and connecting link, and also with a track for a roller which is mounted on said rocker, by means of last named lever; a roller mounted on said pickarm, a runway for said roller having a mutable surface, and being pivotally attached to the frame of the machine; means for controlling the position of said runway including springs, and means for changing the surface of the same including rollers mounted on a slidable frame, a lever adapted to the knee of a human being and pivotally attached to the frame of the machine, an arm and a connecting link.

WALTER C. SYLVESTER.
